United States Patent Office

Des. 186,762
Patented Dec. 1, 1959

186,762

PULL FOR DRAWERS, DOORS AND THE LIKE

Don Heyer, El Monte, Calif., assignor to M and H Industries, Inc., Los Angeles, Calif., a corporation of California

Application December 16, 1958, Serial No. 53,785

Term of patent 14 years

(Cl. D10—8)

Fig. 1 is a front elevational view of a pull for drawers, doors and the like showing my new design;

Fig. 2 is a top plan view thereof;

Fig. 3 is a rear elevation thereof; and

Fig. 4 is an end elevation thereof.

I claim:

The ornamental design for a pull for drawers, doors and the like, as shown.
